UNITED STATES PATENT OFFICE.

JAMES H. O'NEIL, OF SYRACUSE, NEW YORK, ASSIGNOR TO CONTINENTAL CAN COMPANY, INC., OF NEW YORK, N. Y., A CORPORATION OF NEW YORK.

METAL CONTAINER.

Application filed June 23, 1926. Serial No. 118,064.

The invention relates to new and useful improvements in sheet metal containers, and more particularly to a sheet metal container which is provided with means whereby the same may be easily opened.

- An object of the invention is to provide a sheet metal container having a main body portion with an auxiliary body portion attached to the main body portion and extending above the upper edge thereof, which auxiliary body portion is either formed of metal easily severed, or with a scoring line so that it may be easily ruptured, said container also having an end portion which is adapted to be double seamed on to the extension of the body, and said end portion being provided with a depressed portion extending into and frictionally engaging the inner surface of the main body portion.
- 20 A further object of the invention is to provide a sheet metal container of the above type, wherein said body portion is provided with an inwardly projecting shoulder against which the depressed portion of the can end bears so as to prevent the crushing of the auxiliary body portion by endwise pressure on the closed container.

In the drawings which show by way of illustration one embodiment of the invention—

30 Figure 1 is a sectional view through a portion of a metal container on an enlarged scale, which container embodies my invention;

35 Fig. 2 is a view similar to Fig. 1, but showing a slightly modified form of the invention, and

40 Fig. 3 is a view similar to Fig. 1, but showing a still further modified form of the invention.

The improved metal container is formed of sheet metal and includes a main body portion 1 which is preferably cylindrical in shape. Attached to this main body portion is a cylindrical auxiliary body portion or extension 2. In the form of the invention shown in Fig. 1, the main body portion is provided with an inwardly extending shallow bead 3, and the auxiliary body portion 2 is bent inwardly at 4 so as to fit in a recess formed by this shallow bead. The auxiliary body portion is preferably secured to the main body portion by soldering along the lower edge thereof. The main body portion terminates at 5, and the auxiliary body por-

tion 2 extends a considerable distance above the upper end 5. The main body portion is closed at one end thereof by an ordinary end which is attached thereto by a double seam. The other end of the container is closed by an end 6 which is provided with a depressed portion extending down into the auxiliary body portion, and also down into the main body portion where said end makes frictional contact therewith as shown at 7 in Fig. 1 of the drawing. This end 6 is applied by the manufacturer, and the other end applied by the packer.

The end is secured to the auxiliary body portion 2 by an ordinary double seam 8. The central depressed portion of the end extends into the main body portion until it is firmly seated against the hollow shallow bead 3. The auxiliary body portion 2 is preferably made of taggers tin, although it may be made of the ordinary standard tin, and provided with scoring lines for key opening. The essential feature is that the opening of the container shall be accomplished by the severing or rupturing of this auxiliary body portion or extension of the main body portion.

The depressed portion of the can end 6 is provided with an inwardly extending shallow bead 9 in the side wall thereof. The purpose of this shallow bead is to provide a space 10 between the wall of the end and the auxiliary body portion. When it is desired to open the container, a sharp instrument may be run along the lower edge of the double seam and the point will cut through the taggers tin. The space 10 provides ample room for the penetrating end of the instrument so that the instrument may readily follow around the double seam. It is understood, of course, that the drawing is much enlarged and exaggerated as to the shaping of the parts, and the shaping of the parts may be modified, the essential feature being that a space is provided on the inside of the wall of the extension of the body of the container so that said extension may be readily severed at some point above the end 5 of the main body portion of the container, and preferably close to said end. The depressed portion of the end fits into the main body portion and frictionally engages the same. Therefore, after the end has been separated from the body of the container, it may be readily used as a re-closure. Said depressed

portion also rests on the inwardly projecting part of the main body portion, and therefore, any endwise pressure due to the stacking of the closed containers one on another, will 5 not crush or collapse the auxiliary body portion along the lines where it is scored, or if the taggers tin is used. It will be understood that other materials may be used than the taggers tin for providing an extension for 10 the body portion, but it is essential that the material shall be easily severed or ruptured so that the container may be opened after the manner stated above.

The container shown in Fig. 2 of the 15 drawing is similar in construction to that shown in Fig. 1, except the hollow bead in the main body portion of the container is omitted, and said upper end of the main body portion is rolled into a bead 11. In 20 this form of the invention, the depressed portion of the end 6 is made to extend into the main body portion and is provided with a shoulder 12 which rests on the bead 11. Otherwise, the container is similar in construction to that shown in Fig. 1.

In Fig. 3, I have shown a slightly further modified form of the container, in that the auxiliary body portion 2 is secured to the main body portion 1 by a folding of the 30 wall of the body portion inwardly and back upon itself as indicated at 13. The lower end of the auxiliary body portion 2 is bent inwardly at 14 and is gripped by the folded part of the main body portion. It may

also be soldered so as to make a tight connection therewith. The depressed portion of the end rests against the inwardly bent portion of the body after the manner above described.

It will be obvious that minor changes in 40 the details of construction and the arrangement of the parts may be made without departing from the spirit of the invention as set forth in the appended claim.

Having thus described the invention, what 45 I claim as new and desire to secure by Letters-Patent, is—

A container including a main body portion having an inwardly projecting shoulder formed therein, an auxiliary body portion 50 extending down over said main body portion and secured thereto at its lower end, said auxiliary portion extending above the upper edge of said main body portion, an end connected to the auxiliary body portion 55 by a double seam and having a depressed central portion adapted to extend down into said auxiliary body portion and said main body portion and rest against the shoulder in said main body portion so as to prevent 60 endwise pressure on the closed container from distorting or rupturing the auxiliary body portion, said auxiliary body portion being formed of metal which is easily severed or ruptured.

In testimony whereof, I affix my signature.

JAMES H. O'NEILL.
